UNITED STATES PATENT OFFICE

1,999,907

REFRIGERATOR

George Lange, New York, N. Y., and Rudolph Sommers and Mackay C. Saylor, Boston, Mass.

Application October 25, 1932, Serial No. 639,488

15 Claims. (Cl. 62—72)

This invention relates to the art of refrigeration and while the improvements have been designed for use primarily in connection with refrigerators and show cases or counters of all sizes and styles, they are also adaptable for chilling and air conditioning the interiors of buildings, railway cars, and for like purposes. The term "refrigerator" used hereinafter is to be construed broadly as of sufficient scope to apply to any and all of such structures.

It is an object of the invention to utilize ice as the refrigerant and to provide simple and efficient means whereby it is possible not only to maintain a uniform low temperature in the enclosure but also to maintain a high percent of humidity.

Another object is to protect the ice from direct contact with a forced air current flowing through the chamber being cooled, whereby the wasteful melting action due to such contact is avoided and the efficiency of the ice is prolonged.

A still further object is to chill the circulating air solely by contact with a surface extending under and supporting the ice, said surface being maintained constantly at a substantially uniform temperature throughout its area due to the action of ice and ice chilled water contacting therewith.

A further object is to utilize the excess ice water for washing the circulating air, thereby to remove odors and impurities and maintain the proper degree of humidity necessary to prevent deterioration, loss of weight, and other undesirable results obtained through the use of mechanical refrigeration units.

Another and important object is to seal the ice in a compartment provided therefor and to utilize as an air cooling surface only that portion of the structure which extends under and supports the ice and ice water, thereby to insure complete coverage by the refrigerating means of the cooling surface and the maintenance of a desired temperature irrespective of the changing thickness of the ice due to meltage.

A still further and important object is to provide a novel means whereby the retained ice water is in constant contact with the supported ice so that its temperature will be maintained close to the freezing point and it will serve as an efficient supplemental cooling agent.

A further object is to employ a new and novel arrangement of deflectors whereby the transfer of heat units between the circulating air and the cooling surface will be distributed evenly over said cooling surface thereby to effect uniform

meltage over the entire bottom area of the ice and to maintain the ice at a uniform thickness.

With the foregoing and other objects in view which will appear as the description proceeds the invention resides in the combination and arrangement of parts and in the details of construction hereinafter described and claimed it being understood that changes in the precise embodiment of the invention herein disclosed may be made within the scope of what is claimed without departing from the spirit of the invention.

In the accompanying drawings the preferred form of the invention has been shown.

In said drawings:

Figure 1 is a vertical section through a refrigerator equipped with the present improvements.

Figure 2 is an enlarged section on line 2—2, Figure 1.

Figure 3 is an enlarged section on the line 3—3, Figure 1.

Figure 4 is a section on line 4—4, Figure 3.

Figure 5 is an enlarged horizontal section through a portion of the grid, taken on the line 5—5, Figure 1.

Figure 6 is a vertical section showing the invention embodied in a show case or counter refrigerator.

Those who are acquainted with the art of refrigeration are aware of the fact that mechanical refrigeration has many disadvantages which are particularly objectionable where large quantities of supplies are to be kept cold. For example the dehydration of food stuffs results in loss of weight and flavor and produces discoloration, all of which reduce the sales value of the materials

to such an extent as to add greatly to the cost of maintenance. The motor, compressor, and other mechanism necessary to the operation of a mechanical refrigerator require an initial outlay which is beyond the means of many merchants and other potential users, while the cost of repairs and operation constitute another expense which cannot be avoided.

By the use of ice as a refrigerant, the loss of weight and flavor has been avoided to a large extent because of the humidity maintained in the food compartment, and furthermore there has been little waste due to discoloration. However ice has been objectionable because of the rapid meltage and consequent frequent icing required.

The present invention has been perfected for the purpose of overcoming the objectionable features present heretofore in both mechanical and ice refrigerators and to effect not only a considerable saving in the cost of installation, but

also, through the use of certain novel structural features, to maintain an air conditioned storage compartment which will be kept constantly close to a predetermined temperature, the percent of 5 humidity being such as to maintain the weight, flavor and appearance of the stored articles. The invention has also been devised to effect a saving of ice by reducing the rate of meltage so that icing is required only after intervals here- 10 tofore impossible where a uniform temperature has been maintained.

As shown in the drawings the walls 1 of the refrigerator are well insulated. In practice cork board 1 from three to four inches thick has been 15 used. If the refrigerator is a top icer as in Figure 1, it will be provided with an upper or ice chamber 2 and a lower or storage chamber 3. Each chamber will be provided with one or more doors 4 which, when closed, will seal the respective compartments. 20

The two compartments are separated by a partition 5, which can be of wood mounted on cross members 6, and in the illustrated structure this partition extends up to the side walls of the refrigerator but is spaced from the front and back walls so as to provide air passages 7 and 8. Deflecting strips 9 are located at the lower ends of the passages so that descending currents of air will be directed inwardly away from the adjacent 30 walls.

A pan 10 of sheet metal is supported by the partition and has a depending flange 11 which extends around the partition. The pan also has marginal upstanding flanges 12 constituting 35 the front and back walls thereof while flanges 13 at the sides of the pan extend upwardly to constitute the side walls and also to provide means for attachment to the walls of the refrigerator.

Mounted on the pan 10 is a sheet metal grid 14 40 having deep longitudinal corrugations 15 provided with flat inclined walls merging at their tops into upper rounded crown portions 16 and at their bottoms into lower rounded portions 17. These portions 17 cooperate with the upwardly 45 diverging walls of the corrugations to form deep gutters 18, while the upper rounded crown portions 16 cooperate with the walls of the corrugations to form air flues or channels 19 beneath the grid. These gutters are closed at their ends by 50 plates 20 which are soldered to the ends of the corrugated grid plate 14 and fit snugly against and are secured to supporting cleats 21 which overhang passages 7 and 8 as shown particularly in Figure 4. Thus the grid is properly supported 55 both by the cleats 21 and by the pan 10 and, in cooperation with the pan, practically closes one compartment from the other.

The plates 20 are provided with small overflow apertures 22 whereby water can be maintained at 60 a desired depth in the gutters 18 while the overflow will fall into those ends of the pan 10 projecting beyond the plates 20. See Figure 4.

The pan 10 is slightly inclined downwardly toward a central slot 23 extending transversely beneath the corrugated grid and this slot, which is of a length equal to the width of the grid, opens into a flue 24 supported under the partition 5. A blower indicated generally at 25 is adapted to withdraw air from the compartment 3 and force 70 it into flue 24 from which it will flow in a long sheet through slot 23. The bottom of the flue is inclined toward a drain pipe 26 so that excess water passing into the flue from the pan 10 and slot 23 can be carried off.

75 A plate 27 formed with parallel inverted V

shaped corrugations 28 is interposed between the pan 10 and grid 14. These angular corrugations extend upwardly between the gutters 18, and the rounded bottoms 17 of the gutters rest on plate 27 between corrugations 28. The corrugated plate 27 constitutes a baffle or deflector which bridges slot 23 and extends throughout the length thereof. Thus air ascending through the slot will not come directly into contact with the grid but will be deflected along the bottoms of the 10 corrugations 28 and emerge at the ends thereof into the channels 19 where it will contact for the first time directly with the surface of grid 14.

Seated in the channels 19 between the ends of deflector 27 and the ends of the grid corrugations 15 are deflector or baffle strips 29 waved or corrugated as shown and tapered slightly toward the open ends of channels 19. These strips rest on the pan 10 but are attached to the wall of the grid corrugations. The top edges of the strips 20 diverge away from the rounded top portions 16 of the grid in the direction of the open ends of channels 19. Thus air flowing along channels 19 will be split by each strip 29 into two currents which will be deflected toward the flat walls of 25 the channels and flow in gradually increasing volume over the strip into contact with the crown portion 16. The action of these air currents will be apparent clearly by referring to the arrows in Figures 1, 4 and 5.

In practice the door of the ice compartment 2 is 30 opened and after a supply of ice has been placed on the grid 14 so as to cover it to a uniform depth, the door is closed and the compartment thus sealed.

The cakes of ice 1 will rest on the crown portions 35 16 of the grid and because of the conduction of heat therethrough the ice will first melt along these portions and settle down into the upper portions of the gutters 18 where it will be in contact with the downwardly converging flat walls 40 of the gutters. The water W produced by the melted ice will accumulate in the gutters up to the level of the openings 22 and the depending ribs R formed on the bottoms of the lower ice cakes will extend at all times below the level of 45 the water W. Thus the temperature of the water will be maintained close to freezing and all surfaces contacted by the water and ice will be maintained constantly at the same temperature irrespective of the thickness of the ice within the 50 chamber 2. In other words re-icing of the refrigerator can be deferred until the ice has been reduced to a very thin cake and yet there will be no reduction in the temperature of the grid thereunder.

The blower 25 creates a forced circulation of air in the chamber 3, drawing the air from the passages 7 and 8 and directing it into the flue 24. As before stated, air will escape from this flue in a long thin sheet through slot 23. As it 60 enters the space beneath grid 14 it will not come into direct contact with the grid but will come against and be deflected by the corrugated baffle plate 27. The air will then travel along the under side of the corrugated baffle plate and 65 emerge at the ends thereof where it will contact directly for the first time with the walls of the channels 19. Thereafter the air in each end of each channel 19 will be split into two currents passing along opposite sides of the strip 29 in 70 the channel and then be deflected so as to be spread to a gradually increasing extent into intimate contact with the sides and top of the channel. This is due to the corrugations of the strip 29 and also to the fact that the strip is ta- 75

pered away from the top of the channel 19 toward the outlet thereby allowing air in gradually increasing volume to flow over the strip and sweep along the under surface of the crown 16.

5 The baffle plate 27 and the strip 29 are so located and proportioned that the heat exchange will be distributed evenly over the bottom of the grid 14 so that meltage of the ice likewise will be distributed evenly over the bottom surface. As 10 the air does not circulate in the ice chamber 2 and acts to melt only the bottom surface of the ice because only the bottom is affected by conduction of heat, it will be apparent that the ice will melt very slowly in maintaining the desired temperature of grid 14. As the melting action is carried out uniformly along the bottom of the ice 15 the uniform thickness of the ice will be maintained and fewer icings will be required during a given period than have been possible with refrigerators of any other types.

20 As the temperature of the grid is practically unchanged at all times the circulation of the air thereunder will result in the maintenance of a uniform low temperature in the chamber 3. In 25 practice it has been ascertained that with proper insulation, a temperature of 40° to 42° can be maintained continuously.

Aside from the advantages of this structure as 30 a means for maintaining a low uniform temperature, it is advantageous because it will condition the air and hold it at a humidity of 90%. This results from the following action:

As the ice water overflows through the openings 22 it is discharged into the projecting portion of pan 10 thereunder. It then flows along the pan beneath the grid toward slot 23 and thence along flue 24 to the pipe 26. The direction of flow is opposite to that of the circulating air. Consequently the water acts to wash the air, remove all 40 odors and impurities and maintain the desired high percent of humidity so essential to the preservation of food stuffs and other articles without discoloration, taint and loss of weight.

As has already been stated, the present improvements are adaptable to various types of refrigerators and while the structure thus far described is of the type known as a top icer, the same advantageous results can be obtained with a side 45 icer, a display case, or any other design. For example, and as shown in Figure 6, a display case 50 30, suitably insulated, can be formed with an upper display compartment 31, a lower storage compartment 32 and a lower ice compartment 33. The bottom of the ice compartment forms a pan 34 55 supporting a grid 35 corrugated to form air channels separated by gutters, as heretofore described. The air channels 36 under the grid deliver air at one end into a flue 37 leading to a blower 38 located above one end of the ice chamber and discharging into an air space 39 at one end of chamber 31. Outlets 40 are provided for the escape 60 of air from this space into the chamber 31.

An air flue 41 is located at the other end of chamber 31 and communicates therewith through 65 openings 42. This flue leads downwardly to the storage chamber 32 which, in turn, opens into the upper end of a flue 43 opening under one end of grid 35. As the air is warmest where entering beneath the grid 35 it is received at that point by 70 a corrugated baffle plate 44 similar to baffle plate 27 and flows along the under side thereof as indicated by arrows. Thereafter the air enters the unobstructed portions of the channels 36 and then comes into contact with and is split and deflected by the baffle strips 45 which are like the

strips 29 and are provided for the same purpose. Consequently as the air flows under the supported ice there will be an even transfer of heat to insure even meltage of the bottom of the ice. Water in the gutters in the grid will drain therefrom at those ends nearest the flue 37 and flow along the bottom or pan 34 in a direction opposite to the flow of air. Finally the water will enter the drain pipe 46. Obviously in this structure the air will be maintained constantly at a low temperature for the reasons heretofore explained and as the overflow of ice water is into and along the path of the air currents, the desired high percent of humidity will be maintained in both the display compartment and the storage compartment. All walls and the top of the ice compartment are sufficiently insulated to prevent heat exchange therethrough so that when the ice compartment is closed practically no meltage will occur except at the bottom surface of the ice.

What is claimed is:

1. In a refrigerator including an ice chamber and a storage chamber, a pan under the ice chamber having an outlet, a corrugated ice supporting grid providing non-communicating gutters along the top thereof and air conducting channels along the bottom thereof, said channels being closed at the bottom by the pan, there being outlets for the gutters whereby a predetermined level of water is maintained in each gutter and excess water delivered into the pan for movement within and longitudinally of the air channels toward the outlet of the pan.

2. In a refrigerator including an ice chamber and a storage chamber, a pan under the ice chamber having an outlet, a corrugated ice supporting grid providing non-communicating gutters along the top thereof and air conducting channels along the bottom thereof, said channels being closed at the bottom by the pan, there being outlets for the gutters whereby a predetermined level of water is maintained in each gutter and excess water delivered into the pan for movement within and longitudinally of the air channels toward the outlet of the pan, means for directing air into all of the air channels from the storage chamber for movement longitudinally of the channels and over the pan, said air channels having outlets for delivering air therefrom back into the storage chamber.

3. In a refrigerator including an ice chamber and a storage chamber, a pan under the ice chamber having an outlet, a grid having ice supporting corrugations providing non-communicating gutters therebetween below the supported ice for receiving ice water, and air conducting channels along the bottoms of the corrugations and between the gutters, said channels being closed at the bottom by the pan and being cooled at the top by the ice and at the lower sides by the water in the gutters, there being outlets for the gutters whereby a predetermined level of water is maintained in each gutter and excess water delivered into the pan for movement within and longitudinally of the air channels toward the outlet of the pan, means for directing air into all of the air channels from the storage chamber for movement longitudinally of the channels and over the pan, said air channels having outlets for delivering air therefrom back into the storage chamber, and means in each air channel for increasing the volume of air flowing along the upper ice cooled portions of the air channels in proportion to the reduction in temperature of the air in the channels.

4. A refrigerator including an ice chamber and a storage chamber, means for preventing the flow of air from one chamber to the other, said means including an ice supporting grid constituting the bottom of said chamber having gutters for receiving and retaining water produced by the meltage of ice in said chamber, and means for maintaining the surface of the water in the gutters at a level sufficient to contact constantly with the ice supported upon the grid.
5. A refrigerator including an ice chamber and a storage chamber, means for preventing the flow of air from one chamber to the other, said means including an ice supporting grid having gutters extending below the bottom surface of the supported ice for receiving and trapping ice water, there being air passages between the gutters and out of communication with the ice chamber, and means for maintaining the water in the gutters at a predetermined level to cool the bottom and side walls of the gutters and the air passages therebetween and to maintain the surface of the trapped water at a level to constantly contact with the supported ice, said ice constituting means for chilling the top walls of the gutters and the air passages therebetween.
6. In a refrigerator an ice chamber, an ice supporting grid constituting the bottom of said chamber and having non-communicating gutters for receiving ice water and trapping it at and below the level of the supported ice, there being air passages formed by the grid between the gutters, and a second chamber in communication with said air passages, said water-level-maintaining means constituting means for directing surplus water into the air of said second chamber.
7. A refrigerator including a corrugated grid and means contacting and cooperating with the bottom of the grid to provide air passages beneath the grid between its corrugations, the top portions of the corrugations constituting means for direct engagement with supported ice and the gutters between the corrugations constituting means for retaining water below the tops of the corrugations but in contact with portions of the supported ice, the top surfaces of the air passages being maintained by the ice at a temperature lower than but closely approximating the water cooled lower surfaces of the walls of the air passages.
8. A refrigerator having separate compartments normally sealed against the flow of air from one compartment to the other, said refrigerator including a corrugated ice supporting grid constituting the bottom of one of the compartments and providing gutters thereon for the reception of water and providing air passages thereunder and between the gutters, and means for maintaining the water in the gutters at a uniform depth and with its level below the tops of the corrugations, said air passages being extended upwardly to a level higher than the level of the water in the gutters.
9. A refrigerator having separate compartments normally sealed against the flow of air from one compartment to the other, said refrigerator including a corrugated grid for supporting cake ice, said grid constituting the bottom of one of the compartments and providing spaced gutters for receiving ice water, and means for maintaining the water in the gutters at a uniform depth and with its level below the tops of the corrugations, said grid providing air passages thereunder and between the gutters and extending upwardly to a level higher than the level of the water in the gutter, whereby the top walls of the passages will be chilled by direct contact with the supported ice and the lower side walls of the gutters will be chilled by the water in the gutters.
10. The herein-described method of interchanging heat between an air current and a chilling medium which includes the step of directing the air along cooling surfaces to gradually reduce the temperature of the air, and thence along surfaces, chilled by a colder medium, in a volume increasing gradually in proportion to the lowering of the temperature of the air.
11. In a refrigerator an ice chamber, a grid constituting the bottom of said chamber having corrugations forming non-communicating gutters, there being air passages formed by the grid between the gutters, each of said passages having an air inlet and outlet, a second chamber in communication with the inlets and outlets, the tops of the corrugations constituting means for supporting a cake of ice and said gutters constituting means for receiving ice water from the supported ice and trapping it at and below the level of the ice, whereby the tops of the air passages will be maintained at a lower temperature by the supported ice than the water cooled sides of the passages, and sinuous means within each passage between its inlet and outlet for deflecting air in gradually increasing volume against the top of the passage as the air approaches the outlet.
12. In a refrigerator an ice chamber, a grid constituting the bottom of said chamber having corrugations forming non-communicating gutters, there being air passages formed by the grid between the gutters, each of said passages having an air inlet and outlet, a second chamber in communication with the inlets and outlets, the tops of the corrugations constituting means for supporting a cake of ice and said gutters constituting means for receiving ice water from the supported ice and trapping it at and below the level of the ice, whereby the tops of the air passages will be maintained at a lower temperature by the supported ice than the water cooled sides of the passages, and means within each air passage between the inlet and outlet for subjecting air in said passage first to the chilling action of the water cooled sides and thereafter in gradually increasing volume to the chilling action of the ice cooled top as the air flows toward the outlet.
13. In a refrigerator an ice chamber, a grid constituting the bottom of said chamber having corrugations forming non-communicating gutters, there being air passages formed by the grid between the gutters, each of said passages having an air inlet and outlet, a second chamber in communication with the inlets and outlets, the tops of the corrugations constituting means for supporting a cake of ice and said gutters constituting means for receiving ice water from the supported ice and trapping it at and below the level of the ice, whereby the tops of the air passages will be maintained at a lower temperature by the supported ice than the water cooled sides of the passages, sinuous means within each passage between its inlet and outlet for deflecting air in gradually increasing volume against the top of the passage as the air approaches the outlet, and means for maintaining the level of the trapped water in contact with the ice, said level maintaining means constituting means for delivering surplus water into the air below the grid.
14. In a refrigerator an ice chamber, a grid

constituting the bottom of said chamber having corrugations forming non-communicating gutters, there being air passages formed by the grid between the gutters, each of said passages having an air inlet and outlet, a second chamber in communication with the inlets and outlets, the tops of the corrugations constituting means for supporting a cake of ice and said gutters constituting means for receiving ice water from the supported ice and trapping it at and below the level of the ice, whereby the tops of the air passages will be maintained at a lower temperature by the supported ice than the water cooled sides of the passages, means within each air passage between the inlet and outlet for subjecting air in said passage first to the chilling action of the water cooled sides and thereafter in gradually increasing volume to the chilling action of the ice cooled top as the air flows toward the outlet,

and means for maintaining the level of the trapped water in contact with the ice, said level maintaining means constituting means for delivering surplus water into the air below the grid.

15. A refrigerator including an ice chamber and a storage chamber, means for preventing the flow of air from one chamber to the other, said means including gutters in the bottom of the ice chamber for receiving and retaining water produced by the meltage of ice in said chamber, said gutters providing air passages thereunder and therebetween, and means for maintaining the water in the gutters at a level below the tops of the gutters and below the level of the tops of the air passages.
